CLAIM

The ornamental design for a flatware handle, as shown and described.

DESCRIPTION

FIG. 1 is a front view of a flatware handle showing my new design;

FIG. 2 is a right side view of the flatware handle illustrated in FIG. 1, where the left side view is a mirror image thereof; FIG. 3 is a rear view of the flatware handle illustrated in FIG. 1;

FIG. 4 is a cross-sectional view of the flatware handle taken about line A-A illustrated in FIG. 1; and,

FIG. 5 is a cross-sectional view of the flatware handle taken about line B-B illustrated in FIG. 1.

The broken lines in the drawings illustrate the portions of the bottle that form no part of the claimed design.

The dash-dot-dash broken lines in the drawings depict the boundaries of the claimed design.
